UNITED STATES PATENT OFFICE

110,155

DESIGN FOR A BOX COVER

James Quartz, Newton, Mass.

Application February 15, 1938, Serial No. 75,159

Term of patent 14 years

To all whom it may concern:

Be it known that I, James Quartz, a citizen of the United States residing at 17 Washington Street, Newton, in the county of Middlesex and Commonwealth of Massachusetts, have invented a new, original, and ornamental Design for a Box Cover, of which the following is a specification, reference being had to the accompanying drawing, forming a part thereof.

I claim:

The ornamental design for a box cover as shown.

JAMES QUARTZ.
